UNITED STATES PATENT OFFICE.

CHARLES L. SHERIDAN, OF GRYGLA, MINNESOTA.

SLEIGH

1,230,809.

Specification of Letters Patent. Patented June 19, 1917.

Application filed September 8, 1916. Serial No. 119,047.

To all whom it may concern:

Be it known that I, CHARLES L. SHERIDAN, a citizen of the United States, residing at Grygla, in the county of Marshall and State 5 of Minnesota, have invented certain new and useful Improvements in Sleighs; and I do hereby declare the following to be a full, clear, and exact description of the invention, such as will enable others skilled in the art 10 to which it appertains to make and use the same.

This invention relates to motor sleighs, and the primary object of the invention is to provide a sleigh which is particularly 15 adapted for being propelled by an internal combustion engine or other suitable prime mover, which sleigh structure includes a drive shaft having a plurality of levers pivotally mounted thereon and extending longitudinally of the sleigh structure, the rear 20 ends of which levers have an axle rotatably supported thereby upon which are mounted propelling wheels and means to operatively connect the axle to the propelling shaft of 25 the sleigh.

A further object of this invention is to provide means including a plurality of springs, and means for tensioning the springs, which are connected to the forward 30 ends of said levers, for holding the propelling wheels for yieldable engagement with the surface over which the sleigh is traveling.

With the foregoing and other objects in 35 view this invention consists in such novel features of construction, combination and arrangement of parts as will be hereinafter more fully described, illustrated in the accompanying drawings and claimed.

40 In describing the invention in detail reference will be had to the accompanying drawings wherein like characters designate like and corresponding parts throughout the several views, and in which:

45 Figure 1 is a top plan view of the improved motor sleigh.

Fig. 2 is a side elevation of the sleigh.

Fig. 3 is a fragmentary vertical section through the rear portion of the sleigh.

50 Fig. 4 is a cross sectional view through one of the propelling wheels of the sleigh.

Fig. 5 is a detail view of one of the grouters or spurs which are attached to the periphery of the propelling wheel; and

55 Fig. 6 is a view of a modified form of

the grouters or spurs which are attached to the peripheries of the propelling wheels.

Referring more particularly to the drawings, 1 designates the main supporting structure of the motor sleigh which has rear runners 2 supported thereby. The front ends 60 of the runners are connected to the supporting frame 1 by means of flexible members such as chains or the like indicated at 3, which act as safety chains.

65 The rear runners 2 have a bracket structure 2^a attached thereto, the upper end of which bracket structure is pivotally connected by means of a bolt 2^b to a bracing structure generically indicated by the numeral 2^c. 70 The bracing structure 2^c includes a vertical brace 2^d and a side vertical brace 2^e and an angled side brace 2^f. The angled brace 2^f and the vertical side brace 2^e have depending ears 2^g through which the bolts 2^b extend as clearly shown in Fig. 4 of the drawings. 75 The center brace 2^d is connected to the side rails of the supporting frame 1 in any suitable manner as illustrated at 2^h and the lower end of the center brace 2^d is positioned between depending ears 2^k formed upon the horizontal portions of the side braces 2^e and 2^f. A cross brace 2^l is mounted upon the upper end of the braces 2^d, 2^e and 2^f and it extends transversely across the 80 rear end of the frame 1 of the sleigh. A pivotal connection between the brackets 2^a and the bracing structure 2^c permits the rear runners 2 to rock.

85 A power shaft 5 is rotatably supported 90 by the supporting structure 1 and it may be operatively connected through the medium of bevel gears as indicated at 6 to any suitable type of prime mover, such as an internal combustion engine or the like.

95 Levers 7 are pivotally mounted upon the power shaft 5 and have their rear ends bifurcated as shown at 8. The bifurcated ends 8 of the levers 7 rotatably support stub axles 9 upon which are mounted propelling wheels 10. The wheels 10 are positioned between 100 the rear runners, as clearly shown in Fig. 1 of the drawings. The wheels 10 include hubs 10^a, from which a plurality of spokes 10^b radiate. A rim 10^c is mounted upon the outer ends of the spokes 10^b, and it has the spurs or grouters 11 attached thereto, by means of screw threaded shanks 11^a formed upon the inner edges of the blades or grouters 11 as clearly shown in Fig. 6 of the 105 110

drawings. In Fig. 6, the blade of the grouters 11 is pointed, so as to securely bite into the ice or snow over which the sleigh is traveling, while in Fig. 7 of the drawings, 5 the blade 11' has its outer edge straight, as indicated at 11" for use under different conditions, than those for which the blade 11 is designed. Sprockets 12 are mounted upon the stub shaft 9 and sprocket chains 13 10 travel about the sprockets 12 and about sprockets 14 which are mounted upon the shaft 5.

The forward ends of the levers 7 curve upwardly as shown at 15, and they have 15 safety chains 15' attached thereto. Springs 16 are also connected to the curved ends of the levers 7 and these springs are eccentrically connected to disks 20 which are mounted upon a shaft 21. If it is so desired, 20 the springs 16 may be connected to the shaft by a chain or cable, without departing from the spirit of this invention. The shaft 21 is supported by suitable bearings and it has a ratchet 22 mounted thereon intermediate 25 its ends. A hand lever 23 is pivotally mounted upon the shaft 21 and it has a pawl 24 pivotally connected thereto which is adapted for coaction with the peripheral teeth of the ratchet 22 for rotating a shaft 30 21 and the drum 20 for regulating the tension of the springs 16 for increasing or decreasing the spring tension on the levers 7 and consequently on the drive or propelling wheels 10, as desired. If it is so desired, 35 a hand wheel may be mounted upon the shaft 21 in lieu of the lever 23, without departing from the spirit of this invention.

The springs 16 are provided so that the proper tension will be administered to the 40 levers for causing the drive wheels to raise or lower as they pass over uneven places in a road, and for continually keeping the necessary spring tension on the levers, to hold the drive wheels in engagement with 45 the road bed to give the necessary or required grip to propel the sleigh.

Guards 10^a are attached to the rims 10^c of the propelling wheels 10, and extend inwardly toward the hubs 10^a. The guards 50 10^b are substantially V-shaped in cross section and are attached to the spokes by rivets of analogous fastening devices, as shown in Fig. 5 of the drawings.

From the foregoing description taken in 55 connection with the accompanying drawings the advantages of construction and of the method of operation of the improved sleigh will be readily apparent to those skilled in the art to which this invention appertains, 60 and while in the foregoing description, the principle of the operation of this invention has been described together with various features of construction, it is to be understood that certain minor features of construction, combination and arrangement of 65

parts may be altered to suit practical conditions provided such alterations are comprehended within the scope of what is claimed.

What is claimed is:—

1. In a motor sleigh structure, a supporting frame, a power shaft rotatably carried by said supporting frame, a lever pivotally carried by said power shaft and extending longitudinally of said supporting frame, an axle rotatably carried by the rear end of said lever, spurred propelling wheels mounted upon said axle, means operatively connecting said axle and said power shaft for rotating said axle upon rotation of the power shaft, a shaft rotatably carried by said supporting frame forwardly of said power shaft, means for manually rotating said last named shaft, a spring connecting said last named shaft to the forward end of said lever for yieldably supporting said lever for holding said propelling wheels in a land engaging position. 70

2. In a motor sleigh structure, a supporting frame, a power shaft rotatably carried by said supporting frame, a lever pivotally carried by said power shaft, and extending longitudinally of the frame, an axle rotatably carried by the rear end of said lever, propelling wheels mounted upon said axle, 90 means operatively connecting said axle and said power shaft, a shaft rotatably supported by said supporting structure forwardly of said power shaft, a disk mounted upon said last named shaft for rotation therewith, a spring construction eccentrically connected to said disk and connected to the forward end of said lever, means for manually rotating said last named shaft for rotating said disk for tensioning said 95 spring, said spring yieldably supporting said lever for yieldably holding said propelling wheels in a land engaging position. 100

3. In a motor sleigh structure, a supporting frame, a lever pivotally carried by said frame, a propelling wheel carried by the rear end of said lever, a shaft rotatably carried by said supporting frame, means for manually rotating said shaft, a spring connecting said shaft to the forward end of 110 said lever for yieldably supporting said lever for holding said propelling wheel in a land engaging position. 115

4. In a motor sleigh structure, a supporting frame, a lever pivotally carried by said frame, a propelling wheel carried by the rear end of said lever, a shaft rotatably carried by said supporting frame, means for manually rotating said shaft, a disk mounted upon said shaft for rotation therewith, a spring construction eccentrically connected to said disk and connected to the forward end of said lever, a ratchet mounted upon said shaft, a hand lever loosely carried by said shaft, a pawl carried by said 125 130

hand lever for engagement with said ratchet for manually rotating said shaft and disks for tensioning said spring, said spring yieldably supporting said lever for yieldably holding said propelling wheel in a hand engaging position.

In testimony whereof I affix my signature in presence of two witnesses.

CHARLES L. SHERIDAN.
